(57) **CLAIM**

The ornamental design for a game board as shown and described.

DESCRIPTION

FIG. 1 is a top view of a game board, in accordance with an embodiment;

FIG. 2 is a left side view of the game board of FIG. 1;

FIG. 3 is a right side view of the game board of FIG. 1;

FIG. 4 is rear view of the game board of FIG. 1;

FIG. 5 is a front view of the game board of FIG. 1;

FIG. 6 is a bottom view of the game board of FIG. 1;

FIG. 7 is a top view of a game board, in accordance with another embodiment;

FIG. 8 is a left side view of the game board of FIG. 7;

FIG. 9 is a right side view of the game board of FIG. 7;

FIG. 10 is rear view of the game board of FIG. 7;

FIG. 11 is a front view of the game board of FIG. 7; and, FIG. 12 is a bottom view of the game board of FIG. 7.

In the drawings, the dash-dot-dash broken lines indicate boundaries of the claimed design; the evenly spaced broken lines are included for the purpose of illustrating portions of the "article" and forms no part of the claimed design.

1 Claim, 8 Drawing Sheets
